UNITED STATES PATENT OFFICE.

GEORGE H. LANG, OF BOSTON, MASSACHUSETTS.

SPEED-INDICATOR.

1,204,459.

Specification of Letters Patent. Patented Nov. 14, 1916.

Application filed February 10, 1913. Serial No. 747,314.

To all whom it may concern:

Be it known that I, GEORGE H. LANG, a citizen of the United States, residing at Boston, county of Suffolk, State of Massachusetts, have invented an Improvement in Speed-Indicators, of which the following description, in connection with the accompanying drawing, is a specification, like characters on the drawing representing like parts.

This invention relates to speed indicators of that type illustrated in my Patent No. 1,128,695, dated February 16, 1915, and one of the objects of the invention is to provide an improved mechanism of this type having such a construction that when the indicating member is set at the predetermined time intervals said indicating member will move to the proper point to indicate the speed at such time and remain there without any vibration.

Referring to the drawings wherein I have illustrated one embodiment of my invention, Figure 1 is a sectional view through the operative parts of the speed indicator on substantially the line *b*—*b*, Fig. 2; Fig. 2 is a plan view of the mechanism shown in Fig. 1; Fig. 3 is a perspective view of the releasing cam; Fig. 4 is a sectional view on a reduced scale on substantially the line *c*—*c*, Fig. 2; Fig. 5 is a sectional view on substantially the line *d*—*d*, Fig. 2; Fig. 6 is an enlarged section on the line *e*—*e*, Fig. 1.

The main parts of the apparatus herein shown are similar to the corresponding parts of the device shown in said Patent No. 1,128,695. These parts comprise a driving member 40 which is fast on a shaft 41 mounted in a suitable frame 42 and which is intermittently rotated constantly in the same direction at a speed proportionate to that of the machine the speed of which is to be determined, a positioning member 43 which is driven forward and positioned by the driving member 40, and an indicating member 44 which is set at predetermined time intervals to a position determined by the positioning member 43.

The parts thus far described are substantially the same as the corresponding parts in the above mentioned patent, and it will not be necessary to describe them in detail.

The forward rotation of the driving member 40 is effected by a rocking actuator 57 which is pivotally mounted at 58 on the

frame 42. This actuator has one arm 59 which is acted upon by a pneumatic 60 which is connected by a pipe 61 with a pneumatic or pump arrangement associated with the part, the speed of which is to be determined, so that at each revolution or part revolution of said device an air impulse will be forced into the pneumatic 60, thus raising the arm 59. However, it will be obvious that this actuator 57 might be operated in other ways than by pneumatic action without departing from the invention, and I do not wish to be limited herein to any particular means for operating the actuator. This actuator 57 is in the nature of an elbow lever, and each arm thereof carries a pawl which engages the ratchet teeth formed in the periphery of the driving member 40. The arm 59 carries a pawl 62 which is acted upon by a suitable spring 63 and the other arm of the actuator carries a pawl 64 which is pivotally mounted thereto at 65 and is acted upon by a suitable spring 66. The actuator has connected thereto a return spring 67 which returns it to the position shown in Fig. 4 when the air impulse ceases. The arm 59 is raised by the air impulse and the spring 67 returns the parts to normal position. The pump mechanism may be arranged so that there will be one, two or more air impulses at each rotation of the shaft or other part, the speed of which is to be determined, and there will, therefore, be one, two or more oscillations of the actuator at each rotation of said shaft. The purpose of having the two pawls 62 and 64 connected to the actuator on opposite sides of its pivotal point 58 is to provide a construction whereby the driving member will be moved forward during the movement of the actuator in each direction, or, in other words, whereby said driving member will be given two forward movements at each complete back and forth oscillation of the actuator. It will be observed that when the arm 59 is lifted the upright arm of the actuator will move to the right, Fig. 4, and through the pawl 64 will advance the driving member 40. During this movement the pawl 62 will click over the ratchet teeth on the driving member. As the arm 59 of the actuator descends under the influence of the spring 67, the pawl 62 becomes active to continue the forward movement of the driving member and the pawl 64 clicks over the

2
ratchet teeth thereon. By this means the driving member is given a practically continuous forward movement instead of an intermittent movement as would be the case if only one pawl were used. This is an advantage especially in indicators for determining high speeds.

The positioning member is similar to the positioning member shown in the above mentioned patent in that it has a stem 45 which extends axially through the driving member 40 and is provided at one end with a nose 46 adapted to engage any one of a series of ratchet teeth 47 formed on the face 15 of the driving member, this construction providing for clutching the positioning member to the driving member in any relative position of said two members. In the present invention I employ a single spring 20 which operates both to hold said positioning member yieldingly in engagement with the driving member and to return the positioning member to zero position when it is released. The spindle or stem 45 of the positioning member has fast thereto a collar 48 to which is secured one end of a spiral spring 49, the other end of said spring being connected to the driving member. This spring 49 acts not only to yieldingly hold 25 the positioning member in locking engagement with the teeth 47 of the driving member, but it also acts to return the positioning member to zero position against the stop 91 whenever said positioning member is disconnected from the driving member. The forward rotation of the driving member acts on and winds up a main spring 51 which drives the time mechanism the same as described in the above mentioned patent. 30 This spring is housed in a spring barrel 52 which is provided with gear teeth that mesh with and drive a gear 53 on a shaft 54, and said shaft is geared to and drives a shaft 55 carrying an escapement wheel 56, said 35 escapement regulating the speed of the time mechanism in usual manner. The escapement shaft 56 has thereon a releasing cam 68 which releases the positioning member at predetermined time intervals, the cam herein shown being adapted to release said positioning member twice during each rotation of the cam. For this purpose the cam has formed thereon two cam faces 69, see Fig. 3, which are adapted to engage 40 the end of the stem 45 and thereby move said stem axially or longitudinally sufficiently to release the positioning member from the ratchet teeth 47 of the driving member. The spring 49 returns the positioning member into locking engagement with the driving member when the releasing cam has passed out of engagement with the stem 45.

In the device shown in the above mentioned patent the indicating member is posi-

tioned directly by the positioning member, said indicating member being mounted on a shaft which has a ratchet wheel rigid therewith, which ratchet wheel has a stem extending therefrom adapted to be engaged by the positioning member. In the operation of the device shown in said patent the indicating member is first released by the time mechanism and allowed to assume a position determined by the positioning member and the positioning member is then released and returned to zero position while the indicating member is held in the position which it was thus given by the positioning member. With such a construction whenever during any one interval of time the speed of the operating part has decreased, then whenever the time interval expires and the indicating member is released it will move backwardly until the pin above 55 referred to engages the positioning member, after which the positioning member is released. There is, however, a slight interval of time between the instant when the indicating member comes into engagement 60 with the positioning member and the instant when the positioning member is released. During this small interval of time the positioning member is moving forwardly, and as a result each time the indicating member is set it will move back as far as permitted by the positioning member and will then be given a slight forward movement due to the forward movement of the positioning member just before said positioning member is released. This causes the indicating member to have a jerky motion each time that it is re-set which is objectionable in an instrument that is indicating very high speeds. 65

In order to provide a mechanism wherein the indicating member will be re-set at each period of time without any such jerky motion, I have interposed an intermediate member between the positioning member and the indicating member and have arranged the parts so that this intermediate member is first positioned by the positioning member and after the latter is released the indicating member is then positioned by 70 the stationary intermediate member.

The indicating member or pointer 44 is mounted on a shaft 70 which is journaled in a bearing 71 carried by the frame 42 and which has fast thereon a ratchet wheel 72 that is normally engaged by a stop pawl 73, the latter being carried by a shaft 74 that is mounted in the frame 42 and is provided with a releasing finger 75 that is adapted to be engaged by the releasing cam 68. The shaft 70 has a collar 76 fast thereon to which is secured a return spring 77 that tends normally to return the indicating member 44 to zero position. Loosely mounted on the shaft 70 is an intermediate member in the 75

form of a ratchet wheel 78 which is acted upon by a return spring 79 which tends normally to return it to zero position. Said intermediate member 78 has extending therefrom a pin 80 that is adapted to be engaged by the positioning member 43 and said intermediate member is also provided with a projection 81 which may be an extension of the pin 80 or may be a separate projection and which is adapted to engage a pin or projection 82 carried by the ratchet wheel 72. The intermediate member 78 is normally locked from backward rotation by a locking pawl 83 carried by a shaft 84 that is journaled in the frame and which carries at its end a releasing arm 85 that is also adapted to be engaged by the releasing cam 68. The releasing cam 68 has two cam faces 86, one on each end thereof, each of which is adapted to engage the releasing arms 75, 85, successively, these arms being of such a length and so positioned as to result in this successive action, as clearly seen from Fig. 5. With this construction it will be observed that as the releasing cam 68 rotates each cam surface 86 thereon will engage first the releasing finger 85 and then the releasing finger 75 with the result that first the stop pawl 83 will be disengaged from the intermediate member after which the stop pawl 73 will be disengaged from the indicating member. The arrangement of parts is such that this releasing of the intermediate member occurs prior to the releasing of the positioning member, while the releasing of the indicating member does not occur until after the releasing of the positioning member.

From the foregoing it will be readily understood that when the device is idle or inoperative and before it is set in motion the indicating member, the intermediate member and the positioning member will all be at zero position. During the first interval of time after the device is started the forward rotation of the driving member will act through the positioning member and intermediate member to drive the indicating member forward, the stop pawls 73 and 83 clicking over the members 72 and 78 during this forward movement. At the termination of the first time interval the intermediate member 78 is first released but as it is already being driven forward by the positioning member it cannot move backwardly. After the intermediate member is again locked by the holding pawl 83 the positioning member is released and allowed to return to zero position. If during any succeeding interval of time the speed decreases, then at the end of said time interval the releasing cam will first release the stop pawl 83 for the intermediate member, thus allowing it to drop back into engagement with the moving positioning member, and after 65 the stop pawl 83 has again become active the

positioning member is released and returned to zero position, after which the holding pawl 73 for the indicating member is released to allow the indicating member to drop back into the position determined by the intermediate member. The intermediate member, however, is stationary at this time, and, therefore, the indicating member comes into engagement with and its position is determined by a stationary member and not a moving member. The result is that the indicating pointer will have no vibrating or jerky motion when it is brought to rest as would be the case if it were positioned by a moving member. This is an important feature of my invention as it enables me to make an instrument in which the indicating pointer will have a steady movement even though the device is used for indicating relatively high speeds and the indications are made at very short time intervals.

The operative parts of the machine as thus described will preferably be inclosed in a suitable casing in a manner similar to that shown in the above-mentioned patent.

I have shown at 105 a disengaging device for automatically disengaging the positioning member from the driving member whenever the positioning member reaches a certain predetermined position. The object of this device is to prevent the indicating device 44 from running by a predetermined point in case the speed should be increased beyond such point. This disengaging device is in the form of a finger or shield which overlies the ratchet teeth 47, it being herein shown as sustained by a plate 106 which is fixedly secured to the bearing 41 and, therefore, has a stationary position. This disengaging device 105 can be adjusted in any desired position, depending on the speed limit which is to be attained. Whenever during the operation of the device the speed increases up to or beyond such speed limit then the positioning member will be carried from its zero position around to the disengaging device 105 before the expiration of the time interval, and when the nose 46 comes into engagement with the disengaging member 105 said nose becomes disengaged from the driving member and is thus returned to zero position.

While I have illustrated herein a selected embodiment of my invention, I do not wish to be limited to the constructional features shown.

Having fully described my invention, what I claim as new and desire to secure by Letters Patent is:—

1. In a speed indicator, the combination with a rotatable driving member, of means to rotate said member continuously in a forward direction, a positioning member, means to clutch the positioning member periodically to the driving member, an indicating

member, and an intermediate member between the indicating member and positioning member and by which motion is transferred from the positioning member to the indicating member.

2. In a speed indicator, the combination with a rotatable driving member, of means to rotate said member continuously in a forward direction, a positioning member, means 10 to clutch the positioning member periodically to the driving member, an indicating member, a spring tending normally to return the indicating member to zero position, a lock to prevent backward rotation of the 15 indicating member, an intermediate member between the positioning member and the indicating member, means to cause the intermediate member to be positioned periodically by the positioning member and subsequently to release the lock to permit the indicating member to be positioned by the intermediate member.

3. In a speed indicator, the combination with a rotatable driving member, of means 25 to rotate the latter continuously in a forward direction, a positioning member, means to clutch the positioning member periodically to the driving member, means to return the positioning member to zero position 30 when unclutched, an indicating member, a spring tending to return said indicating member to zero position, a lock to restrain such return movement, an intermediate member between the positioning member and indicating member, a spring tending to return the intermediate member to zero position, a lock to restrain such return movement, and means to release momentarily the lock of the intermediate member to permit the latter to 40 be positioned by the positioning member and after said lock becomes operative again to release the lock of the indicating member so

that the latter will be positioned by the intermediate member.

4. In a speed indicator, the combination 45 with a driving member, of means to rotate said driving member continuously in a forward direction, a positioning member, means operative in any relative position of the driving member and positioning member to 50 clutch the latter to the former, an indicating member, an intermediate member, means to position the intermediate member periodically by the positioning member, and immediately thereafter to position the indicating member by the positioned intermediate member.

5. In a speed indicator, the combination with a driving member, of means to rotate 60 said member forward continuously, a positioning member, means operative in any relative position of the driving member and positioning member to clutch the latter to the former, an indicating member, an intermediate member, springs tending normally to return the positioning member, intermediate member and indicating member to their zero 65 positions, locks restraining the return movement of the indicating member and intermediate member, means operated periodically to cause the intermediate member to be positioned by the positioning member and then to disengage the positioning member 70 from the driving member and to release the lock for the indicating member to permit it 75 to be positioned by the positioned intermediate member.

In testimony whereof, I have signed my name to this specification, in the presence of two subscribing witnesses.

GEORGE H. LANG.
